WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,407,065.

Specification of Letters Patent. Patented Feb. 21, 1922.

Application filed December 26, 1916. Serial No. 138,821.

To all whom it may concern:

Be it known that I, WINTHROP K. HOWE, a citizen of the United States, and a resident of the city of Rochester, in the county of 5 Monroe and State of New York, have invented a new and useful Automatic Train-Control System, of which the following is a specification.

This invention relates to automatic train 10 control systems, and more particularly to such systems for controlling the speed of railway trains.

In the type of systems for automatically controlling the speed of railway trains to 15 which this invention more particularly relates, an arbitrary measurable quantity such as position, force or the like which represents and varies with the actual speed of the train, is established on the train, and this quantity 20 is compared with another like arbitrary quantity which is caused to vary as the train progresses so as to assume at different points in the travel of the train a value representing the permissive speed desired at that 25 point; and suitable devices are employed for causing an automatic application of the brakes in case the result of this comparison shows that the actual speed of the train exceeds the desired permissive speed. In applying 30 this system to practical railroad conditions, the railroad is divided into space-units, called blocks, and the system is so constructed and arranged as to provide for the proper control of the speed of the train in 35 any block corresponding to whether or not the next block in advance is occupied by another train. It is a well known fact to those skilled in the art of railway signaling that the different blocks or portions of a railroad 40 under practical conditions are not always of the same grade, so that in applying a system of the type above mentioned to practical railroad conditions it is found desirable to make provision for controlling the speed of 45 the train as it travels over portions of track having different grades.

With these considerations in mind, the primary object of this invention is to devise 50 an arrangement and construction of parts in an automatic train control system such that the speed of the train may be properly controlled although the train travels over different grades along different parts of the railroad.

55 Other objects and advantages will appear

as the description of the invention progresses, and the novel features of the invention will be particularly pointed out in the appended claims.

In describing the invention in detail, reference is had to the accompanying drawing, where I have illustrated a preferred physical embodiment of my invention, and wherein like characters of reference designate corresponding parts throughout the several views, 60 and in which:

Fig. 1 is a diagrammatic view partly in the nature of a wiring diagram, which shows the parts and electrical connections of a speed control system constituting one form 70 of the invention, said parts being illustrated more with a view of making their functions and operations clearly understood than to show their exact construction and arrangement preferably employed in practice; Fig. 75 2 is a section taken along a line extending transversely of the vehicle and extending longitudinally through the selector constituting one of the parts of a system embodying the invention; and Fig. 3 is a plan view 80 of a portion of railroad track illustrating the arrangement of selector ramps.

Referring to the accompanying drawing, the numeral 1 designates a portion of a track rail of the ordinary railroad track upon 85 which the wheels of the vehicle run; and for simplicity only one of the wheels upon which the vehicle is supported is shown, this wheel 2 being connected to the usual axle 3. According to the preferred embodiment of the 90 invention illustrated in the accompanying drawing, communication between the track and the vehicle necessary for the operation of the train control system is obtained by the mechanical and electrical cooperation of 95 a contact shoe carried by the vehicle with ramps or contact rails located at intervals along the track. The contact shoes may be of any suitable construction; and for simplicity are shown diagrammatically in the 100 accompanying drawing as comprising a vertically movable plunger 5, slidably mounted in a bracket 4 carried by the vehicle, said bracket 4 for simplicity being assumed to be made of suitable insulating material. 105 The shoe or plunger 5 is provided with a suitable foot or enlargement at its lower end which constitutes the ramp-engaging portion thereof; and said shoe is pressed downward to its lower position, shown in Fig. 1, 110

2
by a compression spring 7 interposed between a collar 6 fixed to said shoe and the under face of the bracket 4. The shoe 5 is designed to open a circuit when lifted, and 5 to perform this function is shown provided with a button 8 of insulating material, which is larger than the stem portion of said shoe, and which is adapted to form a stop for limiting the downward movement of said shoe; 10 and this button 8 is arranged to lift a contact spring 9 out of electrical contact with a contact piece 10 when said shoe is lifted.

The ramp with which the shoe 5 engages may be of any suitable construction and in 15 general comprises a metallic contacting portion having sloping ends which is supported on any suitable insulating supports adjacent to one of the track rails so as to extend substantially parallel therewith and in 20 the plane of the contact shoe. The electrical cooperation of the contact shoe 5 with the ramp R, utilized for controlling the automatic train control system, is due to the electrical contact of said shoe with the 25 metallic contacting portion of said ramp, during which a partial circuit on the vehicle, hereinafter pointed out, is connected to one of the partial circuits including a source of current which is associated with said 30 ramp, so that electrical energy may be transmitted from the ramp to the vehicle, subject to proper control in accordance with traffic conditions. The partial circuits associated with the ramp R may be of any 35 suitable arrangement, and it is contemplated that these partial circuits will be controlled by the track relays of certain track circuit sections into which the railroad track is divided in the usual manner; but, for simplicity, these trackway circuits are not 40 shown. The source of current associated with the ramp R is shown as comprising a transformer T, the primary 11 of which is connected to a transmission line or an alternating current generator of suitable 45 construction. One terminal of the secondary 12 of the transformer T is connected by a conductor 13 to the track rail 1 and the other terminal of said secondary is connected 50 by conductor 14, switch 15 and conductor 16 to the ramp R. It is apparent that this simplified arrangement provides a means for establishing a difference of potential between the track rail 1 and the ramp R equivalent to the voltage of the secondary 12, 55 and for discontinuing this difference of potential by opening the switch 15.

The parts of the speed control apparatus are preferably in practice suitably supported 60 in a box or casing F, a part of which is shown in the accompanying drawing, and which affords a convenient means for supporting the various parts of the speed control apparatus.

65 The essential parts of the speed control

apparatus are illustrated diagrammatically in the accompanying drawing, and included in these parts is a speed responsive device SI, which is connected to and driven by the wheels of the vehicle, and is so constructed 70 as to show, by the movement given to a part or member, the changes in the speed of the vehicle. In the simplified construction illustrated, a worm 17 is fixed to the axle 3, and meshing with said worm 17 is a worm 75 gear 18 which is secured to the lower end of a shaft 19, said shaft 19 being journaled in suitable supports 20 and being provided with collars 21 pinned thereto, which are disposed above and below said supports 20 80 and serve to prevent endwise movement of said shaft 19. Fixed to the shaft 19 by a pin 23 is a block 22; and slidably mounted on the shaft 19 below the block 22 is another block 24. Connected to the ends of the 85 block 22 are links 25 which are also pivotally connected to weighted balls 26; and, similarly connecting the block 24 to said balls 26 are links 27. A compression coil spring 28 is interposed between the two 90 blocks 22 and 24. Journaled in any suitable manner on a fixed pin 30 is an arm 31 having its free end bifurcated; and supported by the bifurcated ends 32 of said arm are freely revoluble rollers 33, which 95 are disposed between flanges 29 secured to or integral with block 24 of the speed responsive device SI. The operation of the speed responsive device SI is similar to that of the well known governor used for controlling the speed of engines, and will be readily apparent without further explanation.

The device for indicating the permissive speed for the vehicle at different points in 105 its travel, which comprises a cam, is also connected to the wheels of the vehicle, and in the arrangement shown in the drawing this connection comprises a beveled gear 34 fixed to the shaft 19, which meshes with 110 another beveled gear 35 fixed to the end of a shaft 36, which is supported in suitable bearing brackets or lugs 37 integral with or secured to the frame or casing F, said shaft 36 being provided with 115 collars 38 pinned thereto and disposed on opposite sides of the brackets 37 so as to limit the endwise movement of said shaft 36. Fixed to the shaft 36 is a worm 39, which meshes with a gear 40 journaled on a bearing stud or pin 41 fixed to the casing F. A small gear 42 fixed to the gear 40 is also journaled on the pin 41 and meshes with the larger gear 43 journaled on a pin 44 also secured to the casing F; and 120 fixed to the gear 43 is a small gear 45 which meshes with a larger gear 46. In a similar way intermeshing gears 47, 48 and 49 are journaled on bearing studs 50 and 51, and serve to complete a train of gears which 125 130

will be readily recognized as the well known reduction gearing. Jounaled at one end on the pin 51 is a lever 52 to which are rigidly fixed two pins 53 and 54; and mounted on said pins are two intermeshing gears 55 and 56, the gear 56 being also in mesh with the gear 49.

Disposed below the outer or free end of the lever 52 is a cam control magnet C comprising two coils 57, the pole pieces of which are connected at their upper ends by the usual yoke 58, said yoke being bolted to lugs 59 integral with a wall of the casing F. The armature 60 of the cam control magnet C is guided by pins 61 secured in the pole pieces of the coils 57; and this armature 60 is rigidly connected to a rod 62 which extends through an opening in the yoke 58 and is pivotally connected to the outer or free end 20 of the lever 52. A collar 63 is securely fastened to the rod 62, as by a pin, and interposed between the collar 63 and the yoke 58 is a compression coil spring 64 which tends to move the rod 62 and the lever 52 to their 25 lower position opposite to the position shown in Fig. 1.

Jounaled in suitable bearings (not shown) supported by the casing F is a cam-shaft 66 to which is pinned a gear 67, having a small 30 semi-circular portion cut out of its periphery as indicated by the numeral 68. The gear 67 is disposed in the same plane as the gears 55 and 56, hereinbefore described, and is arranged to be driven by said gears at times 35 when the lever 52 is in its lower position. Securely fastened to the cam-shaft 66, as by being pinned thereto, is a cam-shaped plate, hereinafter termed the cam 69. The factors determining the shape of this cam 69 will be 40 pointed out more fully hereinafter. The cam-shaft 66 is provided with suitable means which tends to move said cam-shaft to its initial position shown in Fig. 1; and as a simple means for accomplishing this 45 result, there is shown a counterweight 70 fastened to the gear 67 in position so that when the cam-shaft 66 is free to turn, said counterweight moves the gear 67 and said cam-shaft to the initial position where the counterweight 70 is directly below the axis of 50 said cam-shaft.

Jounaled on a fixed pin 30 is an angle lever L comprising two arms 71 and 72; and arranged below the arm 71 and substantially parallel therewith is an arm 73 which is pivotally supported at one end on a fixed pin 74 and which is pivotally connected at its other end to the lower end of a link 75, said link 75 being adjustable and pivotally 55 connected to the arm 31 in any suitable manner. A link 76 is pivotally connected at its lower end to the arm 73 at a point between the ends thereof, and said link 76 is pivotally connected at its upper end to a 60 block 77 slidably mounted on the arm 71,

the outer end portion of the arm 71 on which the block 77 may slide being curved with a radius equal to the length of the link 76. Secured to the arm 71 are bars 78 which constitute the yokes and supports for a pair 70 of solenoids 79 and 80 having cores 81 which are pivotally connected to the end of a lever 82. Pivotaly connected to a point between the ends of the lever 82 is a link 83 which is pivotally connected to the block 77. Also 75 connected to the lever 82 at a point between its ends is a rod 84 which passes through guiding openings in the yokes 78 of the solenoids 79 and 80; and interposed between the yoke 78 and a collar 85 secured to the rod 84 80 is a compression spring 86 which tends to move the rod 84 and the lever 82 outward from the solenoids 79 and 80.

Carried by the vehicle, preferably by an axle or other part thereof which has a substantially constant relation to the track rails, is a selector which is arranged and constructed so that it may be actuated selectively by suitable devices located at certain places along the track so as to close certain 90 circuits. This selector may take various forms and still accomplish the purposes for which it is used in the system disclosed herein; but in the simplified construction shown in the accompanying drawing, this 95 selector S comprises a frame or casing 87, having a cover 88, which extends transversely of the vehicle and is disposed between the wheels thereof. In the bottom of the casing 87 are guided three vertically 100 movable plungers or tappets 89, 90 and 91 which are formed with enlarged portions or feet at their lower ends. Located at the places along the railroad track where it is desired to operate the selector S are suitable selector ramps (see Fig. 3) which are secured to the ties of the railroad track in any suitable manner between the track rails; and these selector ramps are formed with sloping end portions and are arranged in 110 the plane of the selector tappets 89, 90 and 91 so that as the vehicle passes one of these selector ramps, the selector tappet corresponding to that selector ramp is raised. Since three selector tappets are illustrated 115 in the accompanying drawing, there are shown in Fig. 3 three selector ramps between the track rails, a middle selector ramp M and side selector ramps SR and SL. Referring to Fig. 2, each of the selector tappets 89, 90 and 91 is urged downward to the lower position shown in Fig. 2 by compression springs 92 interposed between the enlarged portions or feet of said selector tappets and the bottom of the casing 87. 120 The two outer or side selector tappets 89 and 91 are pivotally connected at their upper ends to the ends of a floating lever 93; and the middle point of this floating lever 93 is pivotally connected to a contact bar 125

130

94 which is supported by suitable guides (not shown) so as to slide vertically and which carries two insulating contact pieces 95 and 96 arranged to cooperate with suitable contact springs 97, 98, 99 and 100 supported by the casing 87 in any suitable manner and insulated therefrom. Slidably mounted on the upper face of the bottom of the casing 87 is a locking bar 101 which 5 is urged in one direction, toward the left as viewed in Fig. 2, by a tension spring 102. The side selector tappets 89 and 91 pass through holes in the locking bar 101, the righthand faces of each of these holes being 10 beveled, as shown in Fig. 2; and the middle selector tappet 90 extends part way into a similar hole in the locking bar 101 having its right hand face beveled. Secured to or integral with each of the side selector tappets 89 and 91 are locking lugs 103 having beveled faces and squared ends forming shoulders; and the middle selector tappet 90 is formed with a beveled face 104 pressing against the beveled face of the corresponding hole in the locking bar 101. 15

The operation of the simplified form of the selector shown in the drawing is as follows: When either one of the side selector tappets 89 or 91 is raised by one of the side selector ramps SL or SR, the corresponding end of the floating lever 93 is raised so as to bring the lower contact piece 95 into electrical contact with the pair of contact springs 98 and 100. Also, when one of the 20 side selector tappets 89 or 91 is raised the beveled face of the locking lug 103 thereon coacts with the beveled face of the corresponding hole in the locking bar 101 so as to slide the locking bar 101 to the right 25 against the tension of the spring 102 until said selector tappet has moved upward far enough so that the shoulder of the corresponding locking lug 103 is above the upper face of the locking bar 101, whereupon 30 the locking bar 101 is returned to the left by the spring 102, thereby locking the selector tappet which has been raised in its raised position. When both of the side selector tappets 89 and 91 are raised at the same 35 time, both ends of the floating lever 92 are moved upward, and the contact bar 94 is moved to a higher position than when only one of said selector tappets is raised; and the contact piece 96 is moved in position to 40 make electrical contact with its corresponding contact springs 97 and 99. After one or both of the side selector tappets 89 and 91 has been raised and locked in its raised position, the selector tappet or tappets 45 locked in the upper position may be released by raising the middle selector tappet 90. The raising of the middle selector tappet 90 causes the locking bar 101 to move to the right by reason of the cooperation of 50 the beveled face 104 of the selector tappet

90 with the beveled face of the hole in the locking bar 101 through which selector tappet passes; and when the locking bar 101 is moved to the right, any side selector tappet 89 or 91 which may be locked in its upper position is released. Other features of the operation of the selector will be explained hereinafter in the description of the 55 operation.

According to the embodiment of the invention illustrated it is contemplated that the speed of the vehicle will be retarded by the well known system of air brakes; and since this system of brakes is well known to those skilled in the art, it is only necessary 60 to illustrate generally the manner in which the parts of the train control system embodying this invention act so as to cause an automatic application of the brakes. A portion of the train pipe included in the well 65 known system of air brakes is shown in Fig. 1 and designated 105; and connected to said train pipe 105 is a valve 106 of suitable construction having a stem 107 which is controlled by a solenoid 108. It is well understood by those skilled in the art that the venting of the train pipe 105 automatically causes an application of the brakes; and according to the arrangement of parts illustrated, the valve 106 is held closed when 70 the solenoid 108 is energized but is opened by a spring or other suitable means, so as to vent the train pipe 105 when said solenoid 75 is deenergized.

In the construction so far described the 80 arbitrary quantity representing the actual speed of the vehicle is established as different positions of the arm 72 which is caused to assume these different positions in accordance with variations in the actual speed of 85 the vehicle by the operation of the speed responsive device SI and the associated parts connecting said speed responsive device with the arm 72. The arbitrary quantity representing the permissive speed of the vehicle 90 is established as the position of the follower of the cam 69, the cam 69 being connected at times with the wheels of the vehicle and being gradually moved in accordance with the distance traveled by the 95 vehicle. As indicated hereinbefore, the train control system embodying the invention also includes suitable means for comparing the arbitrary quantity representing the actual speed of the vehicle with the arbitrary quantity representing the desired permissive speed for the vehicle, and further for automatically controlling the speed of the vehicle whenever the result of such comparison shows that the actual speed exceeds 100 the desired permissive speed. In the construction illustrated, a floating lever 109 is pivotally connected at its lower end to the arm 72 and carries at its upper end a freely 105 revolvable roller 110 which bears against the 110

edge of the cam 69. A link 111 is pivotally connected at one end to the floating lever at a point between its ends, and said link 111 is pivotally connected at its other end to an 5 arm 112 integral with a contact sector 113 which is mounted for rotation on a suitable fixed pin 114. The edge of the contact sector 113 consists of two concentric portions of different radii connected by an inclined portion 10 constituting a shoulder 115, the purpose of which will be explained more fully hereinafter.

Adjacent to the contact sector 113 is a suitable support 116 integral with or secured to 15 the frame F, and fastened to said support 116 are blocks 117 of suitable insulating material. Connected at one end to the support 116 is a tension spring 118 which is connected at its other end to the arm 112 20 of the contact sector 113. Secured to the block 117 of the support 116 are a plurality of contact supports 119 which support contact fingers 120 and 121 and which also serve as binding posts. Each of the contact fingers 25 120 and 121 is supported on its corresponding support 119 in the same manner, and a description of one will suffice for both. Referring to the contact finger 121, this contact finger is formed at its lower end with a pair 30 of ears 123 which are connected by a horizontal pin to the corresponding contact support 119, so that the contact finger 121 may rock back and forth in a vertical plane. The contact finger 121 is pressed in one direction, toward the left as viewed in Fig. 1, 35 by a compression spring 124 which is mounted upon a pin secured to the corresponding contact support 119 in an obvious manner. Fastened to the contact finger 120 is a 40 bracket carrying a freely revoluble roller 122 of suitable insulating material which is arranged to bear against the edge of the contact sector 113, as clearly shown in Fig. 1. Normally, when the parts are in the 45 position shown in Fig. 1, the contact finger 120 is moved a considerable distance to the right from its contact support 119 against the opposition of the spring 124, while the contact finger 121 is moved only a comparatively short distance from its contact support 119, so that if the contact finger 120 were allowed to move to the left, said contact fingers 120 and 121 would separate, since the contact finger 121 could move only a very 50 short distance as compared with the distance which the contact finger 120 could move.

The speed control apparatus is governed 55 electrically by a relay CS on the vehicle, hereinafter termed the speed control relay; and this relay is provided with two armatures or contact fingers 125 and 126, which are illustrated conventionally. The speed control relay CS is in turn governed by an 60 other relay CP, hereinafter termed the pick-

up relay, which is provided with one armature or contact finger 127.

Operation: The parts of the speed control apparatus are shown in Fig. 1 in the position which they assume when said apparatus, except for imposing a limitation upon the maximum speed which the vehicle may attain at any time, as explained hereinafter, is not acting to control the movement of the vehicle. Disregarding for the present the 75 operation of the parts involved in causing the parts of the train control apparatus to assume this position shown in Fig. 1, which may be termed the normal position, since these features of the operation are to be 80 pointed out hereinafter, it is considered expedient to trace the different controlling circuits for the different parts prior to discussing in detail the successive steps in the 85 operation.

When the parts are in the normal position, the speed control relay CS is energized by a circuit which may be traced as follows: Commencing at the battery 128, conductor 129, relay CS, conductors 130 and 131, armature 125 in its upper position, conductor 132, contact piece 10, contact spring 9, and conductors 133 and 134 back to the 90 battery 128.

The speed control relay CS may be energized so that its armatures may be raised to or held in their upper position when the armature 127 of the pick-up relay CP is raised to its upper position, the circuit for so energizing said relay CS being traced 95 as follows: Commencing at the battery 128, conductor 129, relay CS, conductors 130 and 137, armature 127 in its upper position, and conductors 138 and 134 back to the battery 128. One terminal of the winding of the 100 pick-up relay CP is connected by conductor 135 with the contact shoe 5 and the other terminal of said winding is connected by conductor 136 to the axle 3 or frame of the 105 vehicle.

When the speed control relay CS is energized and its armature 126 is in its upper position, the coils 57 of the cam control magnet C are energized by a circuit which may be traced as follows: Commencing at the battery 139, conductor 140, armature 126 in its upper position, conductor 141, coils 57, and conductor 142 back to the battery 139.

The brake controlling solenoid 108 is normally energized by a circuit which may be traced as follows: Commencing at the battery 143, conductor 144, solenoid 108, conductor 145, contact fingers 120 and 121, and conductor 146 back to the battery 143.

With the parts of the speed control system in the position shown in Fig. 1, the vehicle can not exceed a predetermined maximum speed at any time without having its brakes automatically applied. Referring to 120 125 130

the operation of the parts by means of which this result is accomplished, the speed responsive device SI is shown in Fig. 1 in the position which it assumes when the vehicle 5 is standing still, but when the vehicle commences to move, the arm 31 is moved upward through a certain angle dependent upon the speed of the vehicle by the operation of the speed responsive device SI in a manner 10 which will be readily understood without further explanation. The movement of the arm 31 moves the arm 73 through a corresponding angle by reason of the link 75 connecting said arms; and the movement of the 15 arm 73 causes an upward movement of the link 76 and a resultant upward movement of the arm 71. The arm 72 is integral with or rigidly connected to the arm 71, and consequently as the speed of the vehicle increases 20 this arm 72 is caused to assume positions more and more to the left of the position shown in Fig. 1, thereby resulting in a corresponding movement of the lower end of the floating lever 109 more and more to the 25 left of its position shown in Fig. 1. The cam 69 remains stationary, since the cam control magnet C is assumed to be energized, so that the lever 52 is in its upper position, as shown in Fig. 1, and the gear 55 30 is out of mesh with the gear 67; and consequently the upper end of the floating lever 109 becomes a fixed fulcrum point for said floating lever. With the floating lever 109 fulcrumed at its upper end, as its lower end 35 is moved more and more to the left, due to higher speeds of the vehicle, the link 111 is also moved to the left, thereby causing a turning of the contact sector 113 in the clockwise direction against the opposition of the 40 spring 118; and when the vehicle attains a certain speed, the contact sector 113 is moved far enough so that the shoulder 115 in its edge is brought opposite to the roller 122 secured to the contact finger 120, whereupon 45 the contact fingers 120 and 121 are permitted to separate and interrupt the circuit hereinbefore traced for normally energizing the brake controlling solenoid 108, so as to cause an automatic application of the 50 brakes. The parts are so proportioned in size and position that the automatic application of the brakes occurs in the manner just described whenever the vehicle exceeds a certain predetermined speed which is the 55 desired maximum speed under conditions where the vehicle may proceed without regard for the presence of any other trains. In this way the maximum speed of the vehicle may be controlled and limited to the 60 desired permissive speed.

As indicated hereinbefore, when the system embodying this invention is applied to practical railroad conditions, the railroad track is divided into blocks, and with each 65 block is associated a ramp, as the ramp R.

Associated with each ramp R is a partial circuit, as shown in Fig. 1, which may be closed so as to establish a difference of potential between said ramp and a track rail or which may be opened so that no difference 70 of potential exists. It is contemplated that the means for controlling this partial circuit, represented in Fig. 1 as a switch 15, will in practice be controlled in some suitable manner by means of track relays associated with the blocks, but for simplicity these track-way circuits are not shown. When traffic conditions are such that the vehicle may proceed by a ramp, such as the ramp R, and may travel at any speed less 80 hereinbefore explained until it encounters another ramp, that is, under proceed traffic conditions, the switch 15 will be closed; whereas if it is desired to compel a reduction in the speed of the vehicle after passing a ramp, as the ramp R, either because of the presence of another train ahead or for any other reason, the switch 15 is opened.

When the vehicle equipped with the apparatus as shown in Fig. 1 passes a ramp R, the contact shoe 5 on that vehicle engages said ramp and is raised so as to move the contact spring 9 out of contact with the contact piece 10, thereby interrupting the 90 circuit hereinbefore traced for normally energizing the speed control relay CS. At the same time the contact shoe 5 makes electrical connection with the ramp R, and if the switch 15 associated with that ramp is 95 closed, current is supplied from the transformer T to the pick-up relay CP along a circuit which may be traced as follows: Commencing at the ramp R, contact shoe 5, conductor 135, relay CP, conductor 136 100 through the axles and wheels of the vehicle to the track rail 1, conductor 13, secondary 12 of the transformer T, conductor 14, switch 15, and conductor 16 back to the ramp R.

In this way, under proceed traffic conditions, the switch 15 being closed, although one circuit which normally energizes the speed control relay CS is broken by the mechanical cooperation of the contact shoe 5 with the ramp R, the pick-up relay CP is energized so as to close the other circuit for energizing the speed control relay CS; and consequently under these conditions, the armatures of the speed control relay CS 115 remain in the upper position and hold the parts of the speed control apparatus in the normal position as shown in Fig. 1. It should be noted that while the contact shoe 5 is in engagement with the ramp R and 120 so long as the circuit for normally energizing the speed control relay CS is broken by said contact shoe, the pick-up relay CP is maintained energized and that when the contact shoe 5 leaves engagement with said ramp, 125 130

the circuit for normally energizing the relay CS is established before the pick-up relay CP is deenergized.

In case traffic conditions are such that a vehicle should be compelled to reduce its speed after passing a ramp, as the ramp R, the switch 15 will be opened and no difference of potential will exist between said ramp and a track rail. Under these conditions, when the vehicle passes a ramp R, the circuit for normally energizing the speed control relay CS is interrupted as hereinbefore described, but the pick-up relay CP is not energized, so that all supply of current to the relay CS is cut off and its armatures drop. The dropping of the armature 125 opens a break in the circuit for normally energizing the relay CS, so that after the contact shoe 5 leaves engagement with the ramp R, this circuit will not be established, although the contact spring 9 will be moved again into contact with the contact piece 10. The dropping of the armature 126 of the speed control relay CS interrupts the circuit hereinbefore traced for normally energizing the coils 57 of the cam control magnet C; and the spring 64 pushes the rod 62 downward and moves the lever 52 so as to bring the gear 55 into mesh with the gear 67, whereupon the cam-shaft 66 is operatively connected to the axle 3 of the vehicle and is caused to turn, in one direction or the other, depending upon the direction of rotation of said axle, gradually and exactly in correspondence with the distance traveled by the vehicle.

With the cam-shaft 66 connected to the wheels of the vehicle and gradually turned as the vehicle travels, there commences a gradual reduction in the permissive speed for the vehicle; and unless the actual speed of the vehicle is maintained less than this decreasing speed at all times an automatic application of the brakes will result. This operation is accomplished by the cooperation of the speed responsive device SI and the cam 69. In general, the shape of the cam 69 is determined with reference to the way in which it is desired to gradually decrease the permissive speed for the vehicle, and in practice the shape of the cam is preferably determined from the braking curve of the vehicle with which the cam is associated, with due regard to the extent of movement of the other parts. In the particular construction of the cam shown, the lengths of the radii of the cam are proportional, according to some arbitrary selected scale, to the different permissive speeds desired; and the angular space between the radii of said cam is made proportional, according to some arbitrary selected scale, to distance. The shape of the cam 69 as shown in Fig. 1 is in general the shape of a practical cam for controlling the speed of a rail-

way vehicle, although no attempt has been made to show the precise shape of this cam; and referring to Fig. 1 it can be seen that, as the cam 69 is turned in either direction from its initial or normal position shown in Fig. 1, its radii increase, and due to this increase of the radii of the cam the upper end of the floating lever 109 is caused to assume positions more and more to the left of that shown in Fig. 1 as the vehicle travels. As the upper end of the floating lever 109 is moved more and more to the left, it can be seen that the lower end of said floating lever, which, as explained hereinbefore, is caused to assume positions more and more to the left in accordance with the actual speed of the vehicle, cannot be moved as far to the left, corresponding to higher speeds of the vehicle, without moving the contact sector 113 far enough to bring the shoulder 115 in its edge opposite to the roller 122 so as to result in an automatic application of the brakes. In other words, as the cam 69 is gradually turned by the movement of the vehicle, a gradually decreasing limitation upon the actual speed at which the vehicle may travel is imposed; and this limitation upon the permissive speed is so selected that the vehicle will be brought to a stop or to a predetermined low speed after it has traveled a certain distance, as for example the length of a block. The parts of the apparatus shown in Fig. 1, including the cam 69, are preferably so proportioned that the gradually decreasing limitation upon the permissive speed for the vehicle will accord with the braking curve of the vehicle for the portion of the track over which the vehicle is traveling at the time; but since the braking curve for the vehicle will vary for different portions of the track because, among other things, these portions of track will have different grades, it can be seen that if it is desired to have the gradual decreasing limitation upon the permissive speed for the vehicle follow closely the braking curves of the vehicle for the different portions of the railroad having different grades, it is apparent that some provision must be made to vary the effective action of the cam 69.

According to the embodiment of the invention illustrated, the compensation for the different grades is made by adjusting or changing the operative connection between the speed responsive device SI and the speed arm 72, so that the arbitrary quantity which varies with the actual speed of the vehicle may be caused to vary in such a way that the comparison between this arbitrary quantity and the arbitrary quantity corresponding to permissive speed, which is established by the cam 69, may be used to govern the speed of the vehicle for different grades. It is desirable that the speed arm 72 should cooperate with the cam 69 so as to impose a lim-

itation on the vehicle's speed which will form a curve corresponding with the braking curve for the vehicle, with such margins as may be considered expedient, in order 5 that the vehicle may not be unduly delayed; and since the same correspondence of the curve of limiting speed for the vehicle with its braking curve is desirable regardless of the grade of the track over which the vehicle 10 is traveling, it is desirable to so arrange and construct the parts that the adjustment of the connection between the speed responsive device SI and the speed arm 72 will be made so that the curve of limiting speed for the 15 vehicle with this connection adjusted will accord with the braking curve of the vehicle for the new grade for which this connection is adjusted. In other words, after the speed responsive device SI and its associated parts, 20 together with the particular shape of the cam 69, have been selected so that the curve of limiting speed for the vehicle will accord with the braking curve for the vehicle for one grade, the adjustment made in the connection 25 between said speed responsive device SI and the speed arm 72 should be such that the new curve of limiting speed for the vehicle will accord with the braking curve of the vehicle for the new grade. For these 30 reasons the manner of adjustment of this connection should be selected to accord with the braking curve of the vehicle for different grades; and it is apparent that the relationship between the braking curves of the vehicle for different grades may be such as to require a means for accomplishing the most desirable adjustment which may be different from the particular means herein shown and described.

40 Referring to the particular embodiment of the invention illustrated, the adjustment of the connection between the speed responsive device SI and the speed arm 72 is obtained by changing the position of the sliding block 77 with reference to the axis of the stud 30, so that the effective length of the arm 71, which directly actuates the arm 72, is changed. This movement of the block 77 may be obtained in different ways, but 45 in the construction shown, the block 77 is caused to assume different positions on the arm 71 by operating the selector S and controlling the solenoids 79 and 80. In Fig. 1 the block 77 is shown in the position 50 which it assumes when both of the solenoids 79 and 80 are deenergized, and this position corresponds to the position in which both of the selector tappets 89 and 91 are in the lower position as shown in Fig. 1. As one 55 of the side selector tappets 89 or 91 is lifted by the movement of the vehicle past a place along the track where one of the side selector ramps SR or SL is located, the contact piece 95 is brought into electrical con-

tact with the contact springs 98 and 100, as 65 explained hereinbefore, thereby closing a circuit for energizing the solenoid 79 which may be traced as follows: commencing at the battery 147, conductor 148, solenoid 79, conductor 149, contact spring 100, contact piece 95, contact spring 98, and conductors 150 and 151 back to the battery 147. The energization of the solenoid 79 attracts its core 81, and the floating lever 82 fulcrums about its other end attached to the core 81 75 of the solenoid 80, and the link 83 moves the block 77 toward the right, as viewed in Fig. 1, against the opposition of the spring 86. As explained hereinbefore the side selector tappets 89 and 91, after they have 80 been raised, are locked in the upper position, so that after the vehicle has passed a place where selector ramps are so located as to energize the solenoid 79, this solenoid will remain energized and will hold the 85 block 77 in its shifted position until the vehicle reaches a place where another group of selector ramps is placed. Assume that this second mentioned group of selector ramps is like that shown in Fig. 3, the direction 90 of movement of the vehicle being from left to right; then, when the vehicle passes the middle selector ramp M, the middle tappet 90 of the selector is raised, thereby releasing the side selector tappets 89 and 91 95 and permitting the one which was previously raised to be returned to its lower position by its corresponding spring 92. When the vehicle passes the two side selector ramps SR and SL, the side selector tappets 89 100 and 91 are raised simultaneously and serve to raise both ends of the floating lever 93 the same distance so as to move the contact piece 96 into electrical contact with its co-operating contact springs 97 and 99, so that 105 a circuit for energizing both of the solenoids 79 and 80 is established and may be traced as follows: Commencing at the battery 147, conductor 148, solenoids 79 and 80, conductor 152, contact spring 99, contact piece 110 96, contact spring 97 and conductors 153 and 151 back to the battery 147. When both of the solenoids 79 and 80 are energized, both ends of the floating lever 82 are moved, so that the block 77 is moved farther toward the axis of the stud 30 than when only one of said solenoids is energized. This new selection continues until the selector passes another group of selector tappets which may act to deenergize either or both 115 of the solenoids 79 and 80 and permit the spring 86 to move the block 77 back to its intermediate position or back to the position shown in Fig. 1. Special conditions may make it desirable to arrange the selector 120 ramps differently from the arrangement shown in Fig. 3; but such special conditions do not affect the underlying principles and

mode of operation of the parts embodying this invention and need not be discussed in detail.

When the block 77 is moved along the arm 71 to a point closer to the axis of the stud 30 it shortens the effective length of the arm 71, so that as the arm 73 is raised by the action of the speed responsive device SI, the arm 71 is caused to assume a different position for each position of the arm 73 than it would assume if the block 77 were located at the point on the arm 71 as shown in Fig. 1; and since the effective length of the arm 71 has been shortened said arm 71 will be moved through a larger angular movement for a given angular movement of the arm 73 as it would have been moved if the block 77 were located at the point on the arm 71 as shown in Fig. 1. For example, suppose that a movement of 5 degrees upward of the arm 73 corresponds to an actual speed of the vehicle of 20 miles an hour, it being understood that these figures are assumed merely for the purposes for explanation but are not intended to be necessarily correct for a practical construction; then, if the block 77 is located at such a point on the arm 71 that the effective length of the arm 71 is equal to the distance between the fixed pin 74 about which the arm 73 turns and the point where the link 76 is connected to said arm 73, it can be seen that the arm 71 will be moved through a corresponding angle. If, however, the block 77 is moved toward the right along the arm 71 by the energization of the solenoid 79 or 80, so that the effective length of the arm 71 is shortened, it can be seen that the angle through which the arm 71 moves will be more than 5 degrees. Furthermore, when the effective length of the arm 71 is shortened its movement for each position of the arm 73 will be increased substantially in proportion to the ratio of the effective length of the arm 71 and the distance between the pin 74 and the point where the link 76 is connected to the arm 73; that is, when the block 77 is shifted so as to shorten the effective length of the arm 71, the angular positions assumed by the arm 71 for the different actual speeds of the vehicle will vary from the positions which the arm 71 would assume before the block 77 was shifted in a substantially constant ratio or proportion. Obviously, a change in the angular position which the arm 71 is caused to assume for a given actual speed of the vehicle results in corresponding change of the angular position of the speed arm 72 for that speed of the vehicle, said speed arm 72 being caused to assume the same positions at lower actual speeds, and this means that when the block 77 is shifted to shorten the effective length of the arm 71, the vehicle for any given position of the cam 69, may not attain as

high a speed before an automatic application of the brakes results, than it would be able to attain when the effective length of the arm 71 was longer. The illustration of the invention in the accompanying drawing is diagrammatic in its nature and has been selected with a view of more clearly showing the relation of the several parts than with a view of showing the exact size and proportion of these parts; and it is to be understood that the parts illustrated are not intended to represent the exact dimensions and locations of the parts as they would be constructed to accomplish the desired results.

The simplified type of selector shown is capable of giving only three selections, namely, a selection when both of the selector tappets 89 and 91 are in the lower position; a selection when either of the selector tappets 89 or 91 is raised; and a selection when both of the selector tappets 89 and 91 are raised, the arrangement shown wherein the movement of either of the side selector tappets 89 or 91 causes the same selection, being illustrated with the idea that the vehicle may be headed in either direction when it passes over the selector ramps. Since the simplified form of selector shown is capable of giving only three selections, the solenoids 79 and 80 and their associated parts for shifting the block 77 have been correspondingly illustrated so as to be capable of giving only three positions to said block; but it is apparent that other solenoids and other arrangements of parts may be used so as to permit the block 77 to assume any desired number of positions. For instance, the link 83 is shown in Fig. 1 as connected to the middle point of the floating lever 82, so that, if the solenoids 79 and 80 have the same stroke, the block 77 will be moved to the same position regardless of which solenoid is energized; but it is apparent that by connecting the link 83 to the floating lever 82 at a point nearer one end of said floating lever than the other, the movement given to the block 77 by the energization of one of the solenoids 79 or 80 would be different. Also, in this connection it should be noted that, while in the arrangement and construction of parts shown the block 77 is moved from one position toward the axis of the pin 30 by the energization of the solenoids 79 and 80, it is apparent that other arrangements and construction of parts could be employed so as to cause the block 77 to move outward from the pin 30 as well as inward and to assume any position which may be found desirable.

When the position of the block 77 on the arm 71 is changed by controlling the solenoids 79 and 80, the maximum speed which the vehicle cannot exceed without having its brakes automatically applied is correspondingly changed, since, for any given position

of the cam 69, including its initial or normal position, the speed which the vehicle may attain before an automatic application of the brakes results may be changed by shifting the block 77 on the arm 71 as explained hereinbefore.

It is desirable that the vehicle should in all cases be compelled to reduce its speed to some low limiting speed after it has traveled 10 over the distance for which the cam 69 is shaped; and this low limiting speed may be either zero or some predetermined low speed, as, for example, 5 or 8 miles per hour. In order to accomplish this result, the portion 15 of the arm 71 on which the block 77 may be adjusted is curved in the arc of a circle having a radius equal to the length of the link 76 and having its center coinciding with the pivotal axis of the lower end of the link 76 20 when the arm 73 is in the position corresponding to the low limiting speed desired. To illustrate, the parts shown in Fig. 1 are proportioned and arranged with a view of compelling the vehicle to come to a predetermined low speed; and since this is the result 25 desired, the curved portion of the arm 71 is formed in the arc of a circle having its radius equal to the length of the link 76 and having its center at the pivotal axis at the lower end of the link 76 when the arm 73 is 30 in the position corresponding to said predetermined low speed. Because of this curve of the portion of the arm 71 on which the block 77 is adjusted, the position of the 35 block 77 on the arm 71 has no effect on the angular position of the arm 71 when arm 73 is in the position corresponding to the low speed of the vehicle, so that regardless of the grade for which the block 77 may be adjusted, the vehicle will be brought to the 40 same low limiting speed in all cases.

From the foregoing it can be seen that the curve of limiting speed for the vehicle may be changed without changing the cam 69 by 45 adjusting the parts associated with the speed responsive device SI so that the quantity which is caused to vary with the actual speed of the vehicle may be altered and have different effective values for any one actual 50 speed of the vehicle. As pointed out hereinbefore, one desirable use of this adjustment of the speed responsive device is to compensate for different grades; but it is to be understood that such devices may be used 55 for other purposes for which they are suited. The adjustable connection between the arm 31 and the link 75 permits adjustments to be made so that slight variations in the different speed responsive devices as they are 60 constructed in numbers may be compensated for so as to render said speed responsive devices suitable for use with cams 69 and other parts of the standard shape and size. In this connection it should be noted that since the cam 65 69 is not changed in shape or position, the

distance over which the vehicle travels while its limiting speed is being decreased from some predetermined maximum speed to the low limiting speed remains the same in all cases, so that if the cam 69 is shaped for a 70 particular distance of travel, as a predetermined length of a block, the system will operate to control the speed of the train to the best advantage only for blocks of that length. Consequently, for the proper control 75 of the speed of the vehicle for blocks of different lengths it is desirable to use other cams like the cam 69, or to make some other provision for modifying the effect produced by one cam 69 on the floating lever 109; and it should be clearly understood that where necessary or desirable such expedients may be used in connection with the parts of the system illustrated as embodying this invention. Also, in addition to the automatic 80 application of the brakes, there is preferably employed a warning signal, such as shown and fully explained in my prior application Serial No. 38,132, filed July 6, 1915, but since this use of a warning signal, together with other signals and devices which may be used in connection with the parts as shown in the accompanying drawing and described herein, does not change the operation of the parts more directly concerned in the present 90 invention, these other features have not been shown and described in order to avoid unnecessary complications.

After the parts of the speed control apparatus on the vehicle have been set into operation so as to cause a gradual decrease in the speed of the vehicle, the parts may be restored to their normal or initial condition when the vehicle passes another ramp, providing the partial circuit associated with 100 that ramp is closed so that a difference of potential exists between that ramp and a track rail. When the vehicle passes such an energized ramp, the pick-up relay CP is energized and its armature 127 is raised to close 105 the circuit for energizing the speed control relay CS. When the speed control relay CS is energized in this way, its armatures are raised, and its armature 125 closes one of the breaks in the circuit for normally energizing 110 the said relay CS so that when the contact shoe 5 leaves engagement with the ramp, the armatures of said relay CS will be held in their upper position. The raising of the armature 126 of the relay CS closes the circuit 115 for energizing the coils 57 of the cam control magnet C, and said cam control magnet, being energized, attracts its armature 60 and moves the rod 62 and the lever 52 to the position shown in Fig. 1 where the gear 55 is 120 out of mesh with the gear 67, whereupon the cam-shaft 66 and the parts connected thereto are restored to the normal position by the action of the counterweight 70. After the 125 parts of the speed control apparatus have 130

been restored to their normal or initial position, they are in condition ready for another operation which is caused to occur by the deenergization of the speed control relay CS in the same manner as hereinbefore described.

In order to explain the nature of the present invention, there are shown and described a number of parts and circuits 10 which are disclosed and claimed in other applications.

Although I have particularly described the construction of one physical embodiment of my invention, and explained the operation and principle thereof; nevertheless, I desire to have it understood that the form selected is merely illustrative, but does not exhaust the possible physical embodiments 20 of the idea of means underlying my invention.

What I claim as new and desire to secure by Letters Patent of the United States, is:

1. In an automatic train control system, in combination: a vehicle; means for establishing an arbitrary quantity representing permissive speeds for the vehicle; means on the vehicle for establishing a similar arbitrary quantity representing the actual speed of the vehicle; mechanism controlled jointly by 25 both of said means for controlling the speed of said vehicle; and means for adjusting said second mentioned means to vary the arbitrary quantity established thereby, whereby different limiting speeds at which the 30 vehicle may travel can be obtained for each given permissive speed.

2. In an automatic train control system, in combination: a vehicle; a speed responsive device for indicating the actual speed of 40 the vehicle; permissive speed means for establishing at different points in the travel of the vehicle different permissive speeds for the vehicle; a safety appliance controlled jointly by said speed responsive device and 45 said permissive speed means; and means for adjusting said speed responsive device independently of the permissive speed means to vary its controlling influence upon said safety appliance.

50 3. In an automatic train control system, in combination: a vehicle; means for establishing an arbitrary quantity representing the actual speed of the vehicle; means for establishing a similar quantity representing 55 the permissive speed for the vehicle; a safety appliance for the vehicle governed jointly by both of said means; and means for adjusting said first mentioned means to cause the arbitrary quantity established thereby 60 to vary from predetermined values for corresponding actual speeds to a different value for the respective actual speeds, whereby operation of the safety appliance can be obtained at different actual speeds of the vehicle 65 for a given permissive speed.

4. In an automatic train control system, in combination: a vehicle; means for establishing an arbitrary quantity representing the actual speed of the vehicle; means for establishing a similar arbitrary quantity representing the permissive speed for the vehicle; means for adjusting said first mentioned means to cause the arbitrary quantity established thereby to vary in proportion with the actual speed of the vehicle; and a safety appliance governed jointly by the first two mentioned means.

70 5. In an automatic train control system, in combination: a vehicle; a speed responsive device governed by the rate of movement of the vehicle; a movable member; an adjustable connecting device for operatively connecting said member and said speed responsive device; a second movable member assuming different positions in accordance with 80 the desired permissive speed for the vehicle; a safety appliance governed jointly by said movable members; and means for adjusting said connecting device.

85 6. In an automatic train control system, in combination: a vehicle; a speed responsive device driven by the vehicle; a movable member; an adjustable connecting device for operatively connecting said speed responsive device and said movable member to cause 90 said member to assume different positions to represent the different speeds of the vehicle; and means for adjusting said connecting device to vary the position of said member at each speed in proportion to the speed.

100 7. In an automatic train control system, in combination, means on a vehicle for establishing a series of varying values of arbitrary quantities corresponding with variations in the actual speed of the vehicle, and means for adjusting said means to establish another series of values, each value of said another series bearing a substantially fixed ratio to the corresponding value of the first mentioned series.

105 8. In an automatic train control system, in combination, means on a vehicle responsive to the speed of the vehicle for establishing an arbitrary quantity to represent the actual speed of the vehicle; and means for producing a plurality of adjustments of said means, each of which causes the arbitrary quantity established thereby to vary from predetermined values for corresponding actual speeds to a different value in proportion to the 115 speed.

120 9. In an automatic train control system, in combination: a vehicle; a speed responsive device governed by the rate of movement of the vehicle; a movable member controlled by said speed responsive device; means for multiplying the movement given to said member by said speed responsive device; and means for governing said last mentioned means.

10. In an automatic train control system, in combination: a vehicle and a track therefor; a speed responsive device governed by the rate of movement of the vehicle; a 5 movable member; an adjustable connecting device for operatively connecting said speed responsive device and said movable member; a second movable member assuming different positions in accordance with the permissive 10 speed for the vehicle; mechanism for controlling the movement of the vehicle governed jointly by said members; means for adjusting said connecting device; and means along the track for controlling said last mentioned means.
11. In an automatic train control system, in combination: a vehicle, automatic train control apparatus for the vehicle comprising a speed responsive device connected to 20 the wheels thereof, a movable member, a connection between said member and said device, means for adjusting said connection to cause the member to assume any one of a plurality of different positions for each of 25 the different speeds of the vehicle as indicated by said speed responsive device, and means partly on the vehicle and partly along the track for selectively governing said means to determine the adjustment of said 30 connection.
12. In an automatic train control system, the combination with a vehicle, of automatic speed control apparatus therefor, comprising a speed responsive device, a movable member 35 governed by said device, adjustable means having a plurality of adjustments and acting for each adjustment to cause said member to assume a different position for each given actual speed, and means acting automatically 40 at selected points along the track to control said means.
13. In an automatic train control system, the combination with a vehicle, of a speed responsive device connected to the wheels 45 thereof, a safety appliance for excessive speed including a movable element governed by said device, and means for automatically adjusting the operative connection between said device and said element at different 50 points along the track, thereby causing a different movement of said element for the same actual speed of the vehicle.
14. In an automatic train control system, the combination with a vehicle, of automatic 55 speed control apparatus therefor comprising a speed responsive device, a movable element operatively connected to said speed responsive device and adapted to assume different positions in accordance with the variation in 60 the actual speed of the vehicle, means for producing a plurality of adjustments of the connection between said element and said device, and means for automatically controlling said means at selected points along the 65 track.
15. In an automatic train control system, the combination with a vehicle, of automatic speed control apparatus therefor comprising means governed in accordance with the rate of movement of the vehicle for establishing 70 a measurable quantity varying with the actual speed of the vehicle, means for producing a plurality of adjustments of said means to cause the arbitrary quantity established thereby to vary for the different speeds of 75 the vehicle, and automatic means for selectively determining the effective adjustment at selected points along the track.
16. In an automatic train control system, the combination with a vehicle, of automatic 80 speed control apparatus therefor comprising a speed responsive device connected to the wheels of the vehicle, an element governed by said device and adapted to assume different positions in accordance with the variations in the actual speed of the vehicle, and means partly on the vehicle and partly along 85 the track for adjusting the connection between said element and said device, thereby causing said element to assume any one of a plurality of selected positions corresponding to each actual speed of the vehicle.
17. In an automatic train control system, the combination with a vehicle, of a permissive speed device thereon adapted to change 95 gradually during the progress of the vehicle along the track to impose varying permissive speeds therefor, a safety appliance for excessive speeds, a speed responsive device connected to the wheels of the vehicle, control 100 means for the safety appliance jointly responsive to the permissive speed device and the speed responsive device and acting to cause operation of the safety appliance when the actual speed of the vehicle as determined 105 by the speed responsive device exceeds the prescribed permissive speed, and means for varying the influence exerted by the speed responsive device upon said control means.
18. In an automatic train control system, 110 the combination with a vehicle, of a brake controlling valve, a floating lever controlling the operation of said valve, permissive speed device for controlling one end of the floating lever, a speed responsive device driven by the 115 wheels of the vehicle, an adjustable connection between said devices and the other end of the floating lever and means partly on the vehicle and partly along the track for selectively adjusting said connection.
19. In an automatic train control system, the combination with a vehicle, of automatic speed control apparatus thereon including a safety appliance and a speed responsive device for influencing the operation of said appliance, and means partly on the vehicle and partly along the track for changing the operative connection between said device and said appliance, thereby causing the influence 125 exerted by said device upon said appliance 130

- to be different for each of the different speeds of the vehicle to any one of a plurality of different extents.
20. In an automatic train control system, 5 the combination with a vehicle, of a speed responsive device connected to the wheels of the vehicle, a movable member, an adjustable connection between said device and said member adapted in each adjusted condition 10 to modify the movement of said member as the speed of the vehicle varies, the movement of said member being modified to different extents, in proportion to the speed of the vehicle, and means partly on the vehicle 15 and partly along the track for selectively determining the adjustment of said connection.
21. In an automatic train control system, the combination with a vehicle, of automatic 20 speed control apparatus thereon including a speed responsive device connected to the wheels of the vehicle, an arm moved to different angular positions by said device according to the variations in the actual speed 25 of the vehicle, a safety appliance for excessive speed, a movable member adapted to assume different angular positions for influencing the operation of said appliance, means for connecting said arm and said 30 member, said means being adjustable to change the angular movement given to said member by said arm by any one of a number of different ratios, and automatic means for adjusting the last mentioned means.
- 35 22. In an automatic train control system, the combination with a vehicle, of a permissive speed device adapted to establish permissive speeds for the vehicle during its progress in accordance with a predetermined 40 speed-distance curve, a speed responsive device connected to the wheels of the vehicle, a safety appliance responding to the joint influence of said devices and operated when the actual speed of the vehicle exceeds the 45 prescribed permissive speed, means adapted to modify the influence of the speed responsive device upon said appliance to cause the operation of that appliance to accord with speed-distance curves of different shapes, 50 and automatic means for controlling said means at selected points along the track.
23. In an automatic train control system, the combination with a vehicle, of a speed responsive device connected to the wheels 55 of the vehicle, means governed by said device and changed in accordance with the actual speed of the vehicle, means for causing said means to be changed to a greater extent for the different actual speeds of the 60 vehicle in proportion to such speeds except at a predetermined low actual speed, and means for controlling said last mentioned means at selected points along the track.
24. In an automatic train control system, 65 the combination with a vehicle of a cam
- adapted to be moved in accordance with the distance traveled by the vehicle, said cam acting to establish a curve of limiting speed on the vehicle according with a predetermined speed-distance curve, vehicle controlling means including a speed responsive device connected to the wheels of the vehicle for retarding the movement of the vehicle when its actual speed exceeds the limiting speeds prescribed by said cam, and means 70 operated automatically at selected points along the track for controlling the operative connection between the speed responsive device and the vehicle controlling means to cause the speed-distance curve of limiting 75 speeds to vary.
25. In an automatic train control system, the combination with a vehicle, of automatic speed control apparatus therefor including a speed responsive device connected 80 to the wheels of the vehicle, said apparatus being adapted to retard the vehicle whenever its speed and location exceeds that prescribed by a predetermined speed-distance curve, and means for modifying the influence 85 of said speed responsive device upon said apparatus to cause the vehicle to be controlled in accordance with any one of a number of other speed distance curves.
26. In an automatic speed control system 90 for railway vehicles, speed control apparatus on the vehicle including a speed responsive device and adapted when set into operation to regulate the speed of the vehicle in accordance with a predetermined speed-distance curve, and means operated automatically at selected points along the track 95 for modifying the effective action of said speed responsive device to a predetermined extent variable for the different actual speeds of the vehicle, whereby the speed control apparatus may be adjusted to conform to speed-distance curves of different shapes.
27. In an automatic speed control system 100 for railway vehicles, the combination with automatic speed control apparatus on the vehicle including a speed responsive device, brake controlling means, and a safety appliance for excessive speed influenced by said 105 device and acting to operate said brake controlling means, of adjustable means for modifying the effective action of said speed responsive device upon said safety appliance by a ratio substantially the same for 110 all speeds of the vehicle for each adjustment of said means and automatic means for selectively determining the adjustment to be effective.
28. In an automatic system for governing 115 the speed of railway vehicles, permissive speed means on the vehicle for automatically prescribing limiting speeds therefor at different points in its travel, a speed responsive device governed in accordance with the 120

- movement of the vehicle, brake controlling means subjected to the joint influence of said permissive speed means and said speed responsive device and acting to apply the 45
5 brakes when the speed of the vehicle as determined by said speed responsive device exceeds the permissive speed prescribed by said permissive speed means, and automatic means for selectively causing the effective
10 action of the speed responsive device upon said brake controlling means to vary to predetermined extents for the same actual speed of the vehicle and thereby causing a
15 brake application at different actual speeds of the vehicle for a given permissive speed.
29. Speed control apparatus for railway vehicles, comprising a speed responsive device driven from the wheels thereof, brake control means including a movable member
20 actuated by said device, and adjustable means adapted in each adjusted position to multiply the movement given to said member by said device through a selected ratio.
30. A speed control system for railroads comprising a speed responsive device on a vehicle having a part displaced in accordance with the actual speed of the vehicle, brake control means for the vehicle including a movable member, adjustable means
25 operatively connecting said part and said member and having a plurality of adjusting positions, and automatic means for controlling said adjustable means from the track-
30 way.
31. In an automatic train control system, brake control apparatus on the vehicle including a speed responsive device driven from the wheels thereof, said apparatus being adapted to apply the brakes at different points in the travel of the vehicle in accordance with a predetermined speed distance curve, and means for adjusting the
35 operating connection between said speed re-
40 sponsive device and the other parts of said apparatus to cause the vehicle to be controlled in accordance with another speed distance curve.
32. In an automatic train control system, speed control apparatus and railway vehicle, comprising permissive speed means 50 changeable to different limited speed conditions for the vehicle, a speed responsive device governed in accordance with the movement of the vehicle, a brake-setting appliance, and automatic means adapted to be 55 governed selectively for operating said appliances at different selected actual speeds for each given limiting speed condition of said permissive speed means.
33. Automatic train control apparatus for 60 railway vehicles comprising a speed responsive device connected to the wheels of the vehicle, a movable member actuated by said device, means for adjusting the operating connection between said speed responsive 65 device and said member and thereby causing said member to assume different positions for the same actual speed of the vehicle, and brake controlling means having its operation dependent upon the position of said member.
34. Automatic train control apparatus for railway vehicles comprising a movable member automatically shifted to different positions in accordance with the actual speed of 75 the vehicle, brake controlling means including a movable element and having its operation dependent upon the position of said element, and adjustable means connecting said member and said element, whereby different positions of said element and different resultant control of said brake control means may be obtained for the same actual speed of the vehicle.
